US0D1022186S

(12) **United States Design Patent** (10) **Patent No.:** **US D1,022,186 S**
(45) **Date of Patent:** **** Apr. 9, 2024**

(54) **INCONTINENCE DEVICE**

(71) Applicant: **CNTRL+ INC.**, Cornwall (CA)

(72) Inventor: **Karen Lesley Brunet**, Cornwall (CA)

(73) Assignee: **CNTRL+ INC.**, Cornwall (CA)

(**) Term: **15 Years**

(21) Appl. No.: **35/512,808**

(22) Filed: **Jul. 14, 2021**

(80) **Hague Agreement Data**

Int. Filing Date: **Jul. 14, 2021**

Int. Reg. No.: **DM/215888**

Int. Reg. Date: **Jul. 14, 2021**

Int. Reg. Pub. Date: **Oct. 29, 2021**

(51) **LOC (14) Cl.** **24-02**

(52) **U.S. Cl.**

USPC **D24/122**

(58) **Field of Classification Search**

USPC D24/122

CPC A61F 5/455; A61G 9/00; A61G 9/006
